UNITED STATES PATENT OFFICE.

JAMES W. DAWSON, OF YALESVILLE, CONNECTICUT.

ROTARY EXPLOSIVE-ENGINE.

1,125,486.

Specification of Letters Patent.

Patented Jan. 19, 1915.

Application filed July 27, 1911.

640,744.

To all whom it may concern:

Be it known that I, JAMES W. DAWSON, citizen of the United States, and resident of Yalesville, in the county of Wallingford and State of Connecticut, have invented certain new and useful Improvements in Rotary Explosive-Engines, of which the following is a specification.

My invention relates to certain new and useful improvements in revolving reciprocating explosive engines.

The objects of the invention are to provide an efficient, simple and practical form of air cooled engine that is adapted to produce a great amount of power compared with its weight; to design the motor so as to include three cylinders each of which is to be fired twice with every rotation of the cylinder carrying wheel; and also to have three auxiliary cylinders through which the feed charge is introduced to the explosion cylinders under compression after the closure of the exhaust valve; to inclose and support the wheel in a special form of rim which in part forms the heads for the cylinders and likewise includes cooling means whereby overheating is prevented, and to employ a special form of connecting link intermediate the pistons and crank shafts whereby the said shafts may be located as far as possible from the center and toward the periphery of the cylinder wheel to increase the crank leverage. The three cylinders are placed in triangular form within a revolving wheel that includes a rim which forms heads for the cylinders, and is provided with ribs and perforations to form air passages through which a circulation of air is effected for the purpose of cooling the motor, by drawing the hot air from the inside of the wheel through the perforations of the wheel. Suitable intake ports are provided in the central hollow gear which registers with like ports in the wheel, directly under each cylinder, where the suction is the strongest. The crank case is arranged central of the motor and also serves as a fuel chamber through which the gas is fed to the several cylinders at proper and predetermined intervals. The connecting links are comparatively long and are bifurcated and bowed to straddle and oscillate around the main shaft in a way that forms a unique and compact structure, and in a manner which will not tend to cramp the

pistons by the thrust upon the rod, which by reason of its increased length works more nearly central to the cylinder, and thus limits the forward and backward wear of the piston in the cylinders.

With these and other objects in view the invention resides and consists in the construction and novel combination and arrangement of parts hereinafter fully described, illustrated in the accompanying drawings, and pointed out in the claims hereto appended, it being understood that various changes in the form, proportion, size and minor details of construction within the scope of the claims may be resorted to without departing from the spirit or sacrificing any of the advantages of the invention.

Similar characters of reference denote like or corresponding parts throughout the several figures of the accompanying drawings forming a part of this specification, and upon which,

Figure 1, shows a side elevation of my improved motor complete. Fig. 2, shows a central vertical longitudinal section of the motor shown in Fig. 1. Fig. 3, is a central vertical cross section through the motor shown in the preceding figure and taken on line 3—3 of Fig. 1. Fig. 4, shows a further cross section, partly broken away, and taken on line 4—4 of Fig. 1, and, Fig. 5, shows a detail cross sectional view through one of the exhaust ports and taken on line 5—5 of Fig. 1.

Referring in detail to the characters of reference marked upon the drawings 6 represents the two lower side frame sections of the motor which as will be seen are provided with two supports 7 upon their opposite outer edges, to facilitate the installation of a motor in a car or other vehicle. A pair of somewhat similar upper side frame sections 8 cover the lower frame section and are provided with flanges 9 and bolts 10 for their attachment to the lower sections and the inclosing of the operative parts of the motor. A short cylindrical perforated sheet metal casing 11 is fitted between the said frame members and inside of the flanges 12 to form an inclosure for the periphery of the wheel.

13 represents straps for holding the side frames together and against the tubular outer casing. The connected central part 110

of the side frames 6 and 8 are formed and finished to produce a bearing 14 in which the hubs 15 of the central gears 16 and 17 are mounted. The main shaft 18 is designed 5 to rotate in the said hubs and gears and serves to support the revolving cylinder wheel 19 keyed thereon, between the gears and inside of the frame.

Suitable flat metal rings 20 are fitted between the flanges of the side frames and the outer side portions of the wheel, to form a bearing that may be adjusted and taken up from time to time, by the screws 21 seated in the flanges of the before mentioned side frames. A suitable case 22 is secured to the opposite sides of the wheel by means of screws, and serves to cover and inclose the several gears, except the outside portion of the large central gears 16 and 17. The fuel inlet or feed pipes 23 pass through holes in the central part of the side frames, and are screwed into and made fast to the before mentioned gear 16, which is thus fixed in position, against turning. The shaft, wheel 25 and parts carried therein, thus rotate with respect to the center gears and frame. This gear 16 is hollow to form a passage for the fuel and is provided with two holes 24 in its inner side, which register, at proper 30 times with ports 25 in the side of the wheel, and thus feed the gas into the central chamber 26 from whence it is fed to the several cylinders. The feed ports through the sides of the crank case, are situated directly 35 under the position of each cylinder when drawing in a charge of fuel. This crank case is inclosed on all sides and in practice serves as a fuel mixing chamber by reason of the several connection links operating 40 therein.

The wheel 19 contains three cylinders 27 which are alike in construction and are arranged at an equal distance apart and radially with respect to the axis of the wheel, 45 the central portion of the wheel intermediate of the inner ends of the cylinder forms a combined crank case and fuel chamber. The heads 28 of the cylinders are formed in the rim of the wheel and carry suitable spark 50 ignition plugs 29 which contact with the oppositely located plugs 30 situated at top and bottom of peripheral casing 11. This construction is designed to cause the several cylinders to fire twice with each rotation of 55 the wheel as the said cylinders pass the said outer plugs 30.

The face of the rim of the wheel 19 is provided with several series of peripherally arranged corrugations 31, the channels of 60 which are perforated as shown by 32 to permit of a free flow of hot air out therethrough and a fresh supply of cold air in through the sides and against the cylinders for the purpose of cooling the same.

33 indicates ports leading from the cen-

tral fuel chamber 26 to the several auxiliary or compression cylinders 42 for conveying the fuel to the said cylinders preparatory to passing it into the main cylinder to be fired. This fuel is obviously drawn in by the inward movement of the piston 43 and while the coating piston 34 is in its outer position. By the time the first mentioned pistons 43 have reached their innermost position and began to reverse the mouth 33^a of 70 the port 33 has become closed by the inward movement of the piston 34. This piston 34 is provided with a check valve 44 which allows the fuel to be forced therethrough into the cylinder by the outward movement 75 of the piston 43 preparatory to being fired. The pistons 43 are forced outward to compress the fuel, by means of cams 45 located upon the crank shaft and bearing against the end of said piston. These pistons are 80 drawn back inward by a spring 46 one end of which is connected to said pistons and the other end to the crank bearing.

The exhaust ports 35 are located on the opposite sides from the intake and are so 90 placed with respect to the intake ports, as to insure the cylinders exhausting before the fresh charge of fuel is introduced. The exhaust ports extend out through the sides of the wheel and at proper times register with 95 the two grooves 36 formed in the inner side of rings 20 and extend therethrough and out of the side of the frame.

Each of the pistons 34 are connected by a bifurcated or bowed elongated connecting 100 rod 38, one end of which is connected to the piston and the other end to the crank shaft 39 journaled in the sides of the wheel and having small gears 40 upon their outer end portions and which mesh with the before 105 mentioned large central stationary gear. The main shaft 18 passes freely through the double bowed links just referred to and which operate in an elliptical path with respect to the said shaft. The extreme distance between the center of the wheel and the crank shaft is made possible by the use 110 of these double bowed elongated connecting rods.

The oil is introduced through the pipe 41 115 and enters the hollow gear through the fuel pipe 23 and by way of the above named ports 24 and 25 is fed into the crank case where it comes into direct contact with the pistons and rear end of cylinders at each 120 revolution, and by the centrifugal force is distributed to all internal parts.

The operation, therefore, of my improved engine after the fuel has been turned in, is as follows: The wheel 19 is given a slight 125 starting turn, causing the fuel to be fed in through the central hollow gear to the crank chamber, from whence it is drawn up into the respective auxiliary cylinders, as their intake ports are uncovered. The 130

charges in the several auxiliary cylinders are in turn compressed with the further turning of the wheel, and then forced into the explosion cylinders through the valve 5 44 in the head of the pistons 43 after the closing of the exhaust ports. The spark plug of the first cylinder contacts with that of one of the plugs in the outer casing, to produce the spark and fire the charge. The 10 force of the explosion is transmitted to the crank shaft and small gear, the latter being driven around in mesh with the big fixed gear, transmitting a further rotary motion to the wheel and main shaft. The successive 15 cylinders are in like manner charged and fired twice with each rotation of the wheel, it being apparent that with the three explosion cylinders, each of which fire twice, there are in consequence six charges fired 20 with each rotation of the wheel, thus producing a very effective and rapidly operating motor.

Having thus described my invention what I claim and desire to secure by Letters Patent is:—

1. A rotary explosion engine comprising a shaft, a rotary wheel mounted thereon and having a series of radially disposed cylinders arranged therein, an inclosed fuel chamber central of the wheel and communicating with the said cylinders, crank shafts and gears carried by the wheel and connected to be operated by the cylinders, a central hollow fixed gear meshing with the before mentioned gears, and ports leading from the hollow gear to the fuel chamber for feeding fuel into the revolving cylinder wheel.

2. A rotary explosion engine comprising a rotary wheel having a series of radially disposed and operative cylinders arranged therein, a fuel chamber within the wheel and communicating with the cylinders, a fixed hollow gear adjoining the wheel and having ports to receive the fuel and feed it into the fuel chamber, crank shafts and gears carried by the wheel and meshing with the fixed hollow gear.

3. A rotary explosion engine comprising a shaft, a rotary wheel mounted in the shaft and having a series of radially disposed operative cylinders arranged therein, a piston in each cylinder, crank shafts journaled in the wheel, bifurcated links straddling the shaft and connecting the cylinder pistons and crank shafts, gears upon the crank shafts, and a center fixed gear meshing with the before mentioned crank shaft gears.

4. A rotary explosion engine comprising a frame including a cylindrical casing, a rotary wheel having a series of radially disposed cylinders and operative pistons arranged therein and having the heads of said cylinders formed in the rim of the wheel, a crank shaft for each cylinder and piston, 60 sparking devices in the heads and in the cy-

lindrical casing to cause the cylinders to fire at proper intervals, and bifurcated links connecting the pistons of the cylinders and crank shafts.

5. A rotary explosion engine comprising a central shaft, a rotary wheel mounted thereon having a series of radially disposed cylinders arranged therein, a frame in which the wheel is mounted, an inclosed crank case, central of the wheel forming fuel and mixing chambers, means for directing a supply of fuel through the side of the wheel into said chamber, ports leading from the chamber to the cylinders, and exhaust ports extending from the cylinders through the periphery of the wheel.

6. In a rotary explosion engine, the combination of a frame, central gears fixed therein, a rotary main shaft mounted in the gears, a wheel carried by the shaft and having a series of radially arranged cylinders mounted therein, a piston in each cylinder, crank shafts journaled in the wheel, gears upon said crank shafts meshing with the fixed gears and bifurcated links straddling the main shaft and connecting the pistons of cylinders and crank shafts.

7. A rotary explosion engine comprising a rotary wheel, having a series of radially disposed and operative cylinders arranged therein and a series of compression cylinders arranged directly opposite the before mentioned cylinders, a central shaft upon which the wheel is mounted, crank shafts carried by the wheel directly opposite to the said operative cylinders, and links operating across the central shaft and connecting the pistons of two opposite cylinders and a crank shaft.

8. In a rotary engine, the combination of a frame comprising two pairs of semi-circular side frame members secured together, and a cylindrical casing intermediate of said side members, a shaft and wheel mounted to rotate in the frame and having a series of radial operating cylinders, means to insure the rotation of the wheel by the operation of the cylinders, and means for introducing fuel into the central side portion of the wheel and through the said frame.

9. A rotary explosion engine, comprising a rotary wheel having a series of radially disposed explosion cylinders and pistons arranged therein, a compression cylinder arranged between each two of the said explosive cylinders, a single port leading to each compression cylinder and from the latter to the explosive chambers, a check valve in each of the pistons of the explosion cylinders to permit the fuel to be forced therein, and suitable outlet ports from the said explosion cylinders.

10. A rotary explosion engine, comprising a series of radially disposed explosive cylinders and pistons arranged therein, an in-

closed crank case central of the wheel forming a fuel and mixing chamber, a series of crank shafts operatively mounted within the mixing chamber, bowed bifurcated links connecting the crank shafts with the pistons of the explosion cylinders, a compression cylinder arranged directly opposite each explosion cylinders and having their reciprocating pistons operatively connected with the said bowed links to shove the same back

and forward with the operation of the pistons of the explosion cylinders.

Signed at Bridgeport in the county of Fairfield and State of Connecticut this 24th day of July A. D. 1911.

JAMES W. DAWSON.
